FLUID DELIVERY GUN

Victor S. Faast, Santa Paula, Calif.

Application July 22, 1939, Serial No. 286,041

4 Claims. (Cl. 21—73)

This invention relates to a fluid delivery gun intended principally for injecting liquid into wood or other materials, but also capable of being used for a variety of other purposes.

An important object of the invention is to provide a gun of the kind stated which is adapted to be used for the purpose of rapidly impregnating the timbers of a building with an insecticide fatal to the various types of termites which frequently injure wooden building structures. The improved character of the article for accomplishing this purpose is due to the provision of a superior nozzle structure to prevent the back-flow of the liquid chemical injected into the timbers by the nozzle; to the provision of a nozzle structure capable of being rapidly and effectively hammered into its operative position in relation to the timber to be impregnated with the liquid insecticide; and to the provision of an improved means for graduating the delivery of the liquid from the nozzle.

Other objects and advantages of the invention reside in the provision of an implement whereby the timbers of a building may be more rapidly and efficiently impregnated with a liquid insecticide; the provision of a device which is less tiresome for the workman to use; and the provision of a device whereby the liquid insecticide may be used in a less wasteful manner.

Another important object of the invention is to provide an improved valve cracking means which will permit the impregnating agent to at times drool from the nozzle tip of the instrument.

Still another object of the invention resides in providing a novel combination of nozzle, tip, hammer head, and adjustable valve delivery means with a tank containing a liquid under pressure.

An improved feature of the invention resides in the combination, with a nozzle having a tapered tip at one extremity and an impact receiving portion at its other extremity to drive said tip into a body to be impregnated with liquid from the nozzle; of a flexible conduit connection for supplying liquid under pressure to said nozzle, the flexibility of said connection allowing the device to accommodate itself to the vibrations resulting from delivering blows against its aforementioned impact receiving portion.

The invention further includes an improved means for sealing a blind bore in a wooden or other body and then forcing an impregnating liquid into such sealed bore.

Other objects, advantages, and features of invention will hereinafter appear.

Referring to the drawing wherein is shown a preferred embodiment as now reduced to practice and being introduced to the trade,

Fig. 1 is a view showing the complete device in side elevation, some parts being broken away to show interior construction. In said view, in dotted lines, the valve is shown in cracked or open position.

Fig. 2 is an enlarged section of the nozzle tip occupying its operative position in relation to a piece of wood under treatment. The tip of the valve in the latter view is shown partly in section to reveal its inner construction.

Referring in detail to the drawing, the device comprises a gun 1 including a valve 2, a nozzle 3 fastened to an impact receiving head 4 against which blows may be struck to drive the nozzle into the wood, in combination with a tank 5 for delivering an agent 6 under pressure through the hose 7 to the wooden timber 8 for impregnation.

The nozzle 3 includes a tip 9, provided with a longitudinal restricted aperture 10, which is securely fastened in the end of the nozzle, the tip and adjacent portion of the nozzle being tapered to facilitate driving these parts into the blind hole 11, the nozzle having in a spaced relation to its tipped end a circumferentially extending bead 12, which forms with the wood a leak proof joint, even while the agent being delivered is under impregnating pressure.

Describing in further detail the structures which have been mentioned, the valve 2 is of the pointed, conical type and is contained within a tubular casing 14 having within it a valve chamber 15 furnished with an outlet passage 16, slightly beveled at its inner end to form a seat for the valve 2.

Said valve 2 is carried by an operating stem 17 working through a stuffing box 18 one end of which has a screw-threaded connection with the valve casing, its opposite end portion being externally screw threaded and having screwed on to it a cylindrical, milled nut 19, said nut not only serving to keep in place the stuffing-box sleeve 21, but also, by means of its diametrically reduced outer end portion 22, affording an adjustable stop means for the valve operating lever 23. A coiled compression spring 24 tends to hold the valve 2 against its seat.

The valve casing 14 is carried by a combined support and tubular conduit member 25 of an L shape, the short limb 26 of the L connecting the body portion of said support with said valve

casing, the parts 25, 26, and 14 being desirably made integral. The tubular member 25 extends in a parallel spaced relation to the part of the casing 14 which is furnished with the stuffing box 18. Said member 25 has a laterally extending apertured lug 27 with which the valve operating arm 23 is connected by means of a pivot 28, said arm being shown provided with a bifurcated extension 29 which straddles said lug 27 and is likewise apertured to receive the pivot 28.

The extension 29 of said arm projects laterally from a head or widened end portion 31 thereof, said widened portion having through it an opened passage 32. Said passage affords a clearance around the back end portion of the valve stem 17, which projects thereinto. Through the head 31 of the lever 23 and the passage 32 thereof, extends the valve operating pin 33, said pin also passing through a diametrical hole 34 provided therefor in the back end portion of said valve stem 17. This hole is of a considerably greater diameter than the pin 33, thus allowing a sufficient play for the pin to avoid obstructing the operation of the arm 23 which would otherwise result on account of the arcuate movement of said pin in relation to the reciprocating valve stem.

By preference and as shown, communication between the hose 7 and the tubular member 25 is afforded by means of a metal coupling member 35, the front end of which has a screw-threaded connection 36 with the back end of the member 25 and the opposite end of which is connected with the hose by means of a conventional connection 37. Said member 35 constitutes an extension of the tubular support 25 and, in conjunction with the valve lever 23, completes the handle portion of the device.

The impact receiving member 4 is connected with a tubular shank 41 which is coupled onto the valve casing 14 by means of an expanded internally threaded coupler 42. It is to be understood that the parts 42, 41, 4 and 3 constitute continuous conduit means for conducting fluid from the interior of the valve casing to the nozzle tip 9.

Referring to certain details of construction, the attached nozzle tip 9 is shown having a diametrically reduced shank portion 9a which is wedged in the terminal portion of the main nozzle portion 3 and provides an annular shoulder 9b against which the end of said nozzle abuts.

In the operation of the device for the purpose of impregnating wood with a liquid to destroy termites, a series of blind bores are first drilled into the timbers to be treated, said holes being bored at least to a depth sufficient to admit the tip portion of the nozzle to the depth shown in Fig. 2 where the bead 12 thereof is located somewhat below the top of the bore and space is left for a liquid receiving chamber below the extremity to the nozzle after it has been driven into said bore the proper distance.

Then, after a small portion of the extremity of the nozzle has been inserted into the mouth portion of the bore, the impact receiving head will be struck one or more times with a hammer, thus driving the nozzle into the fully inserted position shown in Fig. 2, wherein the bead 12 will form a seal which will prevent back flow of the liquid when supplied from the reservoir under a pressure desirably between 150 and 200 pounds per square inch. The bead should be made beveled

or rounded, as shown, to lessen obstruction to forcing it down to the sealing position.

The tubular coupling member 35 forms a rearward extension of the main limb of the support 5 25 and thus qualifies said support, in conjunction with the valve operating lever 23, to form an efficient handle means for the device. Said lever may be readily depressed by one part of the hand while another part of the hand abuts against the 10 side of the part 35 opposite thereto. It is only necessary to depress the lever for a brief interval to supply from the nozzle a sufficient quantity of the liquid chemical to impregnate the wood adjacent to each bore 11.

15 A powerful valve spring 24 is provided in order to safeguard against leakage past the valve seat of the pressure impelled liquid.

Hence, unless some provision were made to automatically maintain the valve slightly open, 20 said powerful spring would make it tiresome for the operator to manually maintain the valve in a cracked or slightly open position for any considerable length of time, as is necessary when the device is used to drool a thin stream of the liquid over wooden surfaces, this method of treatment 25 being sometimes desirable, and it is rendered more effective by the combination of the accurately adjustable valve controlling nut 19 with the leak preventing nozzle bead 12. But when this operation is to be performed, the operator 30 will, while holding the valve lever 23 slightly depressed with one hand, use the other hand to adjust the nut 19 to the proper position for stopping the outward swing of lever 23 before the 35 valve reaches its closed position. This will cause a small stream of the poisoned liquid to flow continuously from the nozzle. The provision of the flexible hose 7 as a part of the conduit means imparts to the device the desired freeness of 40 movement required for its operation in both the ways which have been described.

It should be understood that the present disclosure is for the purpose of illustration only and that this invention includes all modifications and 45 equivalents which fall within the scope of the subject matter claimed.

What is claimed is:

1. In a device of the kind described, a combined support, handle means and conduit means; 50 a tubular valve casing carried by said support, a valve in said casing, said valve having an operating stem, a lever connected with said stem to operate said valve, a spring tending to move said valve to its seat, said valve casing having a stuffing box which forms an extension thereof and is furnished with a packing through which said valve stem operates, a tubular nut screwed to said stuffing box through which the stem of said valve extends, said nut having an outer end portion abutting the head of said lever, said nut being adjustable on said stuffing box to limit the movements of said lever which accompany the approach of said valve toward its closed position and thereby regulate the flow of fluid through 55 said valve.

2. In a device of the kind described, a combined support and conduit member having a laterally directed end portion, a tubular valve casing communicating with and carried by said end portion, an end portion of said valve casing extending in a parallel spaced relation to said conduit member, such portion of said valve casing carrying a stuffing box, a valve within said valve casing to control the flow of fluid therethrough, 70 said valve having a stem which extends through 75

said stuffing box and projects therefrom parallel to said conduit member, there being a diametrical hole through such projecting portion of said valve stem, a lever to operate said valve, said lever having a head through which extends a cylindrical passage that surrounds in a spaced relation the projecting end portion of said valve stem, said head carrying a pin which extends across said passage and also passes through said hole through said valve stem, said pin being of considerably less diameter than said hole, said lever having a lateral extension which is pivotally connected with the first recited support and conduit portion, a spring tending to move said valve to its seat, and a tubular nut screwed to said stuffing box through which the stem of said valve loosely extends, said nut having a reduced outer end portion abutting the head of said lever, said nut being adjustable on said stuffing box to limit the movements of said lever which accompany the approach of said valve toward its closed position and thereby regulate the flow of fluid through said valve.

3. In a device of the kind described, a support for a nozzle including a conduit to supply liquid to the nozzle, one section of said conduit constituting handle means for holding the nozzle, said conduit section having an offset portion which is furnished with a valve for said conduit, said valve having a stem in a parallel spaced relation to said conduit section, and an operating lever for said valve stem, said lever extending in an adjacent generally parallel relation to said handle to be graspable in one hand together therewith, and a turnable control means for said valve, said turnable control means comprising a tubular nut screwed to said offset portion through which the stem of said valve loosely extends, said nut having an outer end portion abutting the head of said lever, said nut being adjustable to limit the movements of said lever which accompany the approach of said valve toward its closed position and thereby regulate the flow of fluid through said valve.

4. The combination with a liquid pressure supply means and a nozzle member provided at one end with a fluid delivery tip having a circumfer-

ential bead extending therearound and at its opposite end with an extension suited to receive blows from a hammer directed thereagainst in a direction to force said nozzle tip and head into a woody body adapted for impregnation by a liquid from said pressure supply means, said bead sealing against back flow the liquid ejected from said nozzle into said body; of a manually operable valve controlled fluid gun to regulate the flow of liquid from said pressure supply means to said nozzle tip, said gun having a fluid delivery end in communication with and providing a support for said nozzle member, said gun further comprising a tubular valve casing communicating with said delivery end, a combined support and conduit member connected to said pressure supply means and having a laterally directed end portion connected to and communicating with said tubular valve casing; an end portion of said valve casing extending in a parallel spaced relation to said conduit member, such portion of said valve casing carrying a stuffing box, a valve within said valve casing, said valve having a stem which extends through said stuffing box and projects therefrom parallel to said conduit member, there being a diametrical hole through such projecting portion of said valve stem, a lever to operate said valve, said lever having a head through which extends a tubular passage that surrounds the projecting end portion of said valve stem in a spaced relation thereto to provide for tilting movements of said lever, said head carrying a pin which extends across said passage and also passes through said hole through said valve stem, said pin being of considerably less diameter than said hole, said lever having a lateral extension which is pivotally connected with said conduit member, a spring tending to move said valve to its seat, and a tubular nut screwed to said stuffing box through which the stem of said valve loosely extends, said nut having a reduced outer end portion abutting the head of said lever, said nut being adjustable on said stuffing box to limit the movements of said lever which accompany the approach of said valve toward its closed position and thereby regulate the flow of fluid through said valve.
